UNITED STATES PATENT OFFICE.

GEORGE F. DILLON, OF MCLOUTH, KANSAS.

PACKAGE-TIE.

1,388,176.

Specification of Letters Patent. Patented Aug. 23, 1921.

Application filed October 25, 1920. Serial No. 419,262.

To all whom it may concern:

Be it known that I, GEORGE F. DILLON, a citizen of the United States, and resident of McLouth, county of Jefferson, and State of Kansas, have invented a certain new and useful Improvement in Package-Ties, of which the following is a complete specification.

The present invention relates to package tying devices, and aims to provide a novel and improved form of package tie adapted for quick and convenient application to packages, such as of letters and the like, of varying sizes, and also adapted to be quickly secured to the package as well as removed therefrom with equal facility.

Accordingly, I have devised an improved tie structure which is comprised of a pair of frame members pivotally connected and having one of said members so constructed and arranged as to readily adapt itself to one of the sides of the package in accordance with the thickness or size of the package, the free ends of said frame members being adapted for detachable connection in securing articles together in package form.

Preferably I construct the device of resilient material, such as suitable wire, so as to make the device as strong and at the same time as light as possible, this character of material furthermore lending to the device the necessary yielding and resilient characteristics required for enabling the device to conform itself to packages of different sizes.

It is also sought to provide a device of the character described which will be of cheap and inexpensive construction while sacrificing none of the essential and practical features of the device as an article of utility.

With the foregoing general objects in view, the device will now be described by reference to the accompanying drawing illustrating one form of construction which I have devised for embodying the proposed features of improvement, after which the novel points therein will be particularly set forth and claimed.

In the drawing—

Figure 1 is a perspective view showing a package tie constructed in accordance with the present invention, and spread out in detached form from the package;

Fig. 2 is a perspective view of a package with the parts thereof secured together by means of a package tie embodying the proposed improvement;

Fig. 3 is a plan view, on an enlarged scale, showing one of the frame members of the device, with the other frame member partly broken away.

Referring now to the said drawing in detail, this illustrates the improved device as comprising a frame member 4, preferably constructed of resilient wire material, in approximately rectangular form, and suitable for application to one of the sides of a package, such as a number of letters 5 assembled in package form, as illustrated in Fig. 2. At one of its ends, the frame member 4 has the end portions of the wire forming said frame coiled or twisted to provide an extension 6 terminating in a pair of oppositely extending hooks 7, for detachable engagement with the free end of the other frame member hereinafter described. At its opposite end the frame member 4 is formed with a short extension 8, to the opposite sides of which is attached a short length of resilient wire, the middle portion 9 of which connects the sides of the extension 8, about which sides of said extension the wire is coiled to produce a pair of spring coils 10 terminating in short arms 12, the action of the spring coils 10 being such as to maintain the arms 12 normally in substantially co-planar relation to the frame 4, as is represented in Figs. 1 and 3.

Pivotaly connected with the arms 12 is a second frame member, also preferably of spring wire material, the middle portion of which is coiled to provide a pair of spring coils 14 wound about the opposite sides of a loop 15 at the middle of the free end portion of said second frame; the remaining or free end portions of the wire composing the second frame are bent to form an approximately rectangular frame, the ends of the portions 16 being formed with eyes 17 adapted for pivotal and sliding engagement with the arms 12, from which they are prevented from becoming separated by reason of terminal coils 18 provided on the ends of said arms 12.

From the foregoing description, with reference particularly to Figs. 1 and 2 of the drawing, the mode of use of the device will be readily understood. The frame 4 is of practically fixed form, adapted for application to one of the sides of the package, and the action of the spring members 10 as well as of the coils 14 is such as to maintain the parts of the second frame (formed of the

wire portions 16 and arms 12) normally in a substantially flat outline; but, this action being of a yielding character, the said second frame may be folded somewhat about 5 the axis of the coil springs 10 and 14 as well as about its pivotal connection with the arms 12 for conforming the parts of the second frame to the size and shape of the package comprised of the articles 5. Thus the device 10 is readily adjusted to accommodate itself to the size and shape of package, to which the parts of the device are secured by engagement of the loop 15 with either of the hook terminals 7 of the frame member 4, it being 15 understood that the second frame may be swung in either direction about its pivotal connection with the arms 12 and thereby engaged with either of said hook terminals 7, according to which side of the frame 4 is applied 20 against the face of the package. When the device is secured to the package as shown in Fig. 2, the spring or resilient character of the connections between the frame portions of the device is such as to securely 25 hold the articles of the package together, while of course permitting one or more of said articles to be withdrawn from the package, as is customary in certain lines of work, particularly in the work of mail carriers. 30

From the foregoing it will be seen that I have devised a simple, practical and efficient, and at the same time inexpensive form of device for carrying out the desired objects 35 of the invention, and while I have shown what is now thought to be the preferred form of construction I desire to reserve the right to make such changes as may fairly fall within the scope of the following 40 claims.

What I claim is:

1. A package tie comprising a frame member adapted to be applied to one side of the package, and a second frame member 45 composed of folding sections adapted yieldingly to assume a normally substantially flat outline with relation to the other side of the package and provided with a flexible connection with one end of said first frame member, the free end portions of said frame members being adapted for detachable connection. 50

2. A package tie comprising a frame member adapted to be applied to one side of the package, and a second frame member composed of folding sections adapted yieldingly to assume a normally substantially flat outline with relation to the other side of the package and provided with a spring 55 hinge connection with one end of said first frame, the free end portions of said frame members being adapted for detachable connection. 60

3. A package tie comprising a frame member adapted to be applied to one side 65

of the package, and a second frame member composed of folding sections provided with a spring-hinge connection with one end of said first frame member, the free end of said second frame having a spring-hinge 70 structure coöperating with said connection to maintain said second frame normally in a flat outline, the free end portions of said frame members being adapted for detachable connection. 75

4. A package tie comprising a frame member adapted to be applied to one side of the package, one end of said frame being composed of folding sections provided with a pair of spring arms lying normally in substantially coplanar relation to said frame, a second frame member pivotally connected at one end to said frame and provided at its opposite end with a spring-hinge structure coöperating with said arms to maintain said second frame normally in a flat outline, the free end portions of said frame members being adapted for detachable connection. 80 85

5. A package tie comprising a frame member adapted to be applied to one side of the package, one end of said frame being provided with a pair of spring arms lying normally in substantially coplanar relation to said frame, a second frame member pivotally connected at one end to said arms for swinging movement in either direction with reference to said arms, said second frame having a spring-hinge structure coöperating with said arms to maintain said second frame normally in a flat outline, and means for detachably connecting the free ends of said frames with said second frame at either side of said first frame. 90 95 100

6. A package tie comprising a resilient wire frame member adapted to be applied to one side of the package, one end of said frame being formed with a pair of spring arms extending in opposite directions and lying normally in substantially coplanar relation to said frame, and a second resilient wire frame member pivotally connected at one end to said arms and provided with a spring-hinge structure at its other end coöperating with said arms to maintain said second frame normally in a flat outline, the free end portions of said frame members being adapted for detachable connection. 110 115 120

7. A package tie comprising a wire frame adapted to be applied to one side of a package and formed of two members having a spring-hinge connection at one of their ends, a pair of spring arms pivotally connected to the other ends of said frame, a second wire frame having one end connected to said spring arms, and means for detachably securing the other end of said second frame to said spring-hinge connection of said first-named frame so that said second frame may be applied to the opposite side of a package from said first frame. 125 130

8. A package tie comprising a wire frame adapted to be applied to one side of a package and formed of members having a coiled spring-hinge connection at one of their ends 5 adapted to maintain said members in coplanar relation, a pair of spring arms pivotally connected to the other ends of said members, a second wire frame secured to said spring arms, and means secured to said second frame adapted to detachably underlie the coiled spring-hinge connection of said first-named frame so that said second frame may be applied to the opposite side of a package from said first frame. 10

In witness whereof I hereto affix my signature. 15

GEORGE F. DILLON.
